UNITED STATES PATENT OFFICE.

EDWARD J. GLACKIN, OF CHICAGO, ILLINOIS.

VENTILATOR.

SPECIFICATION forming part of Letters Patent No. 733,956, dated July 21, 1903.

Application filed March 6, 1902. Serial No. 96,929. (No model.)

To all whom it may concern:

Be it known that I, EDWARD J. GLACKIN, a citizen of the United States, residing at Chicago, in the county of Cook and State of Illinois, have invented certain new and useful Improvements in Ventilators, of which the following is a specification.

My invention is concerned with certain new and useful improvements in ventilators, and is designed to produce a device of the class described which may be applied to a window or similar structure, preferably at the top thereof, and which can be adjusted so as to direct the current of air entering upward toward the ceiling and prevent the possibility of a direct draft striking the occupants of the room.

My invention is also concerned with the combination of a device of the class described with a window-shade, whereby the ventilator can be adjusted at any necessary angle without interfering in any manner with the operation of the shade. It is also preferably constructed so that the shade itself forms a part of the ventilator.

To illustrate my invention, I annex hereto two sheets of drawings in which the same reference characters are used to designate identical parts in all the figures, of which—

Figure 1 is a perspective view of the upper half of a window, showing my improved ventilator applied thereto and in use. Fig. 2 is a central longitudinal section through the window with the parts adjusted as they are in Fig. 1. Fig. 3 is an enlarged view similar to Fig. 2, but with the window closed and the ventilator not in use; and Fig. 4 is a view similar to Fig. 3, but showing the ventilator arranged inside the window-frame and modified to adapt it for such a location.

a represents the ordinary window-frame, in which the upper and lower sashes *b* and *c* are mounted to slide in the customary manner. On each side, near the top of the frame, I secure, by screws or otherwise, the bearing-plate *d*, which has pivotally secured to the outer end thereof and on the inner face, as at *e*, the side piece *f* of the ventilator-frame.

These two side pieces are preferably of the triangular shape shown and are each provided at their lower end with the inwardly-projecting thimble *g*. These two thimbles *g* serve as the support for the rod *h*, which connects the two side pieces. In the upper ends of the side pieces *f* is mounted a curtain-roller *j*, which is preferably of the customary spring-roller construction and has mounted thereon the shade *k*. The side pieces *f* are provided on their front edges with the inwardly-projecting flanges *l*, which extend inward far enough to cover the edges of the curtain. In connection with the ventilator a pair of strings *m* and *n* are employed, which are secured thereto in any convenient manner, as by being fastened to the rings *o* and *p*, which in turn are passed through suitable holes in the top of the side pieces. The string *n* is passed rearward and through a ring or sheave *q*, so that by pulling down on the cord *m* the ventilator may be tilted forward to the position shown in Figs. 1 and 2, or by pulling the cord *n* it may be turned back to its vertical or inoperative position. (Shown in Figs. 3 and 4.) These cords *m* and *n* may have their lower ends secured in any desired manner to hold the ventilator in any position of adjustment, or the lower ends may be connected as shown and passed over the customary cord-tightener *r*, suitably located upon the window-casing.

The operation of the device will be readily apparent. When the window is closed and in the position shown in Fig. 3, the ventilator may stand in the vertical position therein shown, and the shade *k* hangs straight down in the normal manner. If it is desired to ventilate the room, the upper sash *b* is drawn down a short distance and the cord or cords *m* are pulled down to swing the rear of the ventilator, and consequently the curtain, against the upper portion of the sash *b*. In this position it will be apparent that the air entering must be directed toward the top of the room and the heated air already in the room can readily escape through the opening, the ventilator thus providing for the inward and outward drafts without the possi-

bility of creating a draft in the lower portion of the room, where it will be injurious to the occupants.

In case the ventilator is to be employed in connection with a very deep window-frame, such as is shown in Fig. 4, it is necessary to mount the ventilator within the frame, and in that case in addition to the mechanism heretofore described I may employ a supplemental strip *s* on both sides, which may be formed integral with or fastened to the frame in connection with the bearing-plate *d*. This supplemental strip *s* has an elongated vertical slot *t* therein which serves to support the ends of the transverse strip *u*, which I employ to lower the draft at the top of the window enough so that it will strike the ventilator when in the operative position shown in dotted lines in Fig. 4, so that the current of air will be necessarily deflected upward, as in the ordinary construction.

While I have shown my invention as embodied in the form which I at present consider best adapted to carry out its purposes, it will be understood that it is capable of modifications and that I do not desire to be limited in the interpretation of the following claims except as may be necessitated by the state of the prior art.

30. What I claim as new, and desire to secure by Letters Patent of the United States, is—

1. In a device of the class described, the combination with the window-casing having the sashes therein, of the ventilator pivotally mounted to the casing on the inside of the window at one end thereof and normally hanging parallel thereto when the window is closed in position so that it can be swung from the vertical position it normally occupies to any desired inclination to bring its lower edge against the displaced sash to coöperate therewith for the purpose described, and means for swinging said ventilator and for securing it in the position to which it may be moved.

45. 2. In a device of the class described, the combination with the window-casing having the sashes therein, of the ventilator consisting of the side pieces *f* pivoted to the casing intermediate their ends, and the body portion connecting said sides and normally hanging parallel to the window when closed in position so that it can be swung from the vertical position it normally occupies to any desired inclination to bring its lower edge against the displaced sash to coöperate therewith for the purpose described, means for swinging said ventilator, and means for securing said ventilator in the position to which it may be moved.

50. 3. In a device of the class described, the combination with the window-casing and the sashes movable therein, of the ventilator consisting of the side pieces *f* pivotally secured intermediate their ends to said casing near

the upper end thereof, the rod *h* connecting 65 the lower ends of said side pieces *f*, the curtain-roller mounted in the upper end of said side pieces, and the curtain mounted on said roller and coöperating with the rod.

4. In a device of the class described, the 70 combination with the window-casing and the sashes movable therein, of the ventilator consisting of the side pieces *f* pivotally secured intermediate their ends to said casing near the upper end thereof, the rod *h* connecting 75 the lower ends of said side pieces *f*, the curtain-roller mounted in the upper end of said side pieces, the curtain mounted on said roller and coöperating with the rod, and means for swinging said ventilator to any desired position of adjustment and securing it in said position.

5. In a device of the class described, the 80 combination with the window-casing and the sashes movable therein, of the ventilator consisting of the side pieces *f* pivotally secured intermediate their ends to said casing near the upper end thereof, the rod *h* connecting 85 the lower ends of the said side pieces *f*, the curtain-roller mounted in the upper end of 90 said side pieces, the curtain mounted on said roller and coöperating with the rod, and means for swinging said ventilator to any desired position of adjustment and securing it in said position and consisting of the cords 95 secured to the upper end thereof coöperating with the adjusting mechanism *r*.

6. In a device of the class described, the combination with the side pieces *f* provided with means for pivotally securing them intermediate their ends to the casing of the window near the upper end thereof, the rod *h* connecting the lower ends of said side pieces *f*, the curtain-roller *j* mounted in the upper 100 end of said side pieces *f*, and the curtain on 105 said roller adapted to coöperate with the other parts, substantially as and for the purpose described.

7. In a device of the class described, the combination with the side pieces *f* provided 110 with means for pivotally securing them intermediate their ends to the sides of the window-casing near the upper end thereof, and with the thimbles *g* and the flanges *l*, of the rod *h* extending between said thimbles, the curtain-roller *j* mounted in the upper end of said side 115 pieces, the curtain coöperating with said roller, and means for swinging said side pieces to, and securing them in, any desired position of adjustment.

8. In a device of the class described, the combination with the side pieces *f* provided 120 with means for pivotally securing them intermediate their ends to the sides of the window-casing near the upper end thereof, and with the thimbles *g* and the flanges *l*, of the rod *h* extending between said thimbles, the curtain-roller *j* mounted in the upper ends of said side 125

pieces, the curtain coöperating with said roller, and means for swinging said side pieces to, and securing them in, any desired position of adjustment consisting of the

5 springs *m* and *n* secured to the upper end of the side pieces *f* and on opposite sides thereof and the holding mechanism *r* with which said springs coöperate.

9. In a device of the class described, the
10 combination with the ventilator adapted to be

pivottally secured on the inside of the window-casing, of the transverse piece *u* adapted to extend across the top of the casing for the purpose described.

In testimony whereof I affix my signature 15
in presence of two witnesses.

EDWARD J. GLACKIN.
